CLAIM

The ornamental design for a combined receptacle adapter and light, as shown and described.

DESCRIPTION

FIG. 1 is a front, left side perspective view of a combined receptacle adapter and light;

FIG. 2 is a front view thereof;

FIG. 3 is a left side elevational view thereof, the right side elevational view being a mirror image;

FIG. 4 is a top view thereof;

FIG. 5 is a bottom view thereof; and,

FIG. 6 is a rear elevational view thereof.

The broken lines are shown for illustrative purposes only and form no part of the claimed design.
